DIAMOND SET CORE BIT

Leo Catallo, Detroit, Mich., assignor to Wheel Trueing Tool Company, Detroit, Mich., a corporation of Delaware

Application September 14, 1949, Serial No. 115,618

1 Claim. (Cl. 255—72)

1

This invention relates to a core bit and more particularly to a diamond set core bit for drilling oil wells.

As is customary in drilling operations, a drilling fluid, or drilling "mud" as it is called, is pumped down through the hollow drilling head assembly to flow outwardly over the working face of the drill bit and upwardly in the hole or well. In the case of diamond set bits, surges in the fluid pressure at the bottom of the hole will often cause bumping of the working end of the bit against the bottom of the hole with consequent damage to the diamonds by being broken against hard formations. Such surging may be due to pump surges or to faulty pump circulation, but bumping may also be caused by the provision of water courses in the working face of the bit of insufficient volume to accommodate the volume of circulating fluid that must escape from the inside of the bit to the outside if a balanced flow is to be maintained. If an out-of-balance condition obtains, sufficient pressure may build up to lift the bit up off the bottom of the hole, with the result that when this excess pressure is relieved suddenly, the weight of the drilling equipment may force the bit down against the bottom of the hole with a striking blow that may break the diamonds in the working face of the bit.

I have now found that by a proper construction and design of a diamond set core bit and with a novel arrangement of water courses, the tendency of excess fluid pressure to build up and relieve itself in the manner described is largely minimized or even eliminated entirely. This result is accomplished in accordance with the principles of my invention by providing auxiliary water grooves in a novel and effective arrangement with respect to the working face of the core bit and the positioning of the diamonds, or other abrasive particles, set therein.

It is therefore an important object of this invention to provide a diamond set core bit of novel and improved construction and design in the use of which there is less tendency of the diamonds becoming broken by percussive impact against hard drilling formations.

Other and further important objects of this invention will be apparent from the disclosures in the specification and the accompanying drawings.

As shown on the drawings:

Figure 1 is a bottom plan view of a diamond set core bit embodying the principles of my invention.

Figure 2 is a sectional view taken substantially along the broken line II—II of Figure 1.

On the drawings:

The reference numeral 10 indicates generally a diamond set core bit embodying the principles of my invention. Said core bit 10 comprises an

2

annular body 11, formed of metal or of a metallic alloy, and presenting inner and outer surfaces 12 and 13 joined by an upper convex surface 14. The inner and outer surfaces 12 and 13 are substantially cylindrical and are relieved at their ends, as at 15 and 16, to form annular shoulders that lie in longitudinally spaced planes. Said shoulders 15 and 16 have functional purposes in connection with the other elements of the drilling head assembly with which the core bit 10 is to be associated in the setting up of the drilling equipment. The convex end surface 14 smoothly joins the inner and outer cylindrical surfaces 12 and 13 but with a curve of lesser radius to form the inner contour 17 than the radius of the curve forming the outer contour 18.

The surfaces 12, 14 and 13 constitute the working face of the core bit and, for this purpose, are set with abrasive particles, or diamonds, indicated at 19. The diamonds 19 are individually set in the mold used in making the core bit 10, and are arranged in predetermined patterns and with varying lengths of the diamonds protruding from the surface of the body, or matrix, in which the diamonds are set. For instance, the diamonds 19 over the end surface 14 protrude rather substantially from the surface in which they are set, but the diamonds, indicated at 19a, along the outer cylindrical surface 13 gradually become flush with the surface down toward the lower end, or shoulder 16 of said surface.

The working face of the core bit is provided with a plurality of symmetrically arranged radiating grooves 20, which serve as water courses for the flow of drilling fluid from the interior of the drilling assembly radially across the working face of the core bit and upwardly along the outer surface 13. Said main water grooves 20 lie in planes passing through the axis of the core bit and divide the working face of the core bit into sector-shaped portions indicated at S. The main grooves 20 are segmentally circular in cross section and are of substantially uniform cross section throughout their lengths, terminating on the inside at the shoulder 15, as at 20a, and at the outside at the shoulder 16, as at 20b. In addition to the main water grooves, there are the usual junk grooves 21, of which four are shown equi-spaced about the periphery of the core bit. The junk grooves are for facilitating the escape of junk iron that may be found in the hole, provided the junk iron is in small enough particle size. In order to prevent damage to the diamonds of the core bit, all foreign objects should be kept out of the hole, or should be removed before starting the diamond drilling operation.

My observations as to the operation of diamond set core bits provided with water courses arranged as are the water courses 20 in the accompanying drawings have led me to the con-

clusion that similar arrangements of water courses in the core bits heretofore used are not sufficient of themselves to make for efficient operation of the core bit in service. I have observed that there is a tendency, where such prior arrangements of water courses have been employed, for pressure to develop in the drilling fluid at the bottom of the hole sufficient to raise the working face of the core bit out of contact with such bottom wall of the hole, with the result that when this excess fluid pressure is relieved, as will occur necessarily, the weight of the drilling equipment will force the working face of the core bit against the bottom of the hole with a percussive impact that frequently results in damage to the diamonds. As is well known, diamonds are comparatively fragile toward shocks due to impact, and must be protected insofar as possible against such shocks if they are to give good service in drilling operations.

In order to eliminate this tendency of the drilling fluid to build up excessive pressure beneath the working face of the core bit, I provide auxiliary water courses, indicated at 22, which lie along medial planes of the sector-shaped portions S and extend from near the middle of the convex end face 14 and continuously along the outer cylindrical surface 13 to the shoulder 16. These auxiliary water grooves 22 provide a relief for the excess of drilling fluid that may flow out of the main water grooves 20 and across the end face 14 of the core bit between the protruding rows of diamonds 19. Thus, the auxiliary grooves serve to relieve the building up of pressure that might otherwise result in a pounding of the core bit against the bottom of the hole. This same effect would not be produced by continuing the auxiliary grooves 22 completely across the convex end face 14 and down along the inner and outer cylindrical surfaces 12 and 13 (as do the main water grooves 20), since if that were done the effect obtained would be no different from that obtained by increasing the number of the main water grooves.

The important thing seems to be to provide for an increase in the volume capacity of the water grooves from a point at, or near, the peak of the convex surface 14 and outwardly thereof to the end of the outer cylindrical surface 13.

As shown on the drawings, the diamonds 19 are arranged with radially extending rows of diamonds, such as the rows R, R extending continuously from the inner cylindrical surface 12 radially outwardly over the convex surface 14 and down along the outer cylindrical surface 13, each of the two rows R, R, substantially paralleling the adjacent main water groove 20. Since the rows R, R are thus outwardly divergent from each other, it is necessary in order to provide adequate density of diamonds on the working face of the core bit to set other rows of diamonds, such as the rows R', R', inside of the outer rows R, R. Said rows R', R' start on the inside of the convex surface 14 as a row of single diamonds and then spread into a double row toward the outside of the convex surface 14 to lie on either side of the auxiliary water grooves 22. As a result of this arrangement, the density of the diamonds, or the number of diamonds per unit area of the sector-shaped portions S, is maintained substantially uniformly over the working face of the core bit. However, as previously explained, the diamonds 19a along the cylindrical outer surface 13 protrude less and less, until they lie substantially flush with the surface 13 toward the

end of said surface that is defined by the shoulder 16. The diamonds 19a thus serve to maintain the diameter of the hole that is drilled, while the diamonds nearer the beginning of the convex portion 14 serve both a reaming as well as a drilling function, and the same is true of the diamonds on the inner end of the convex surface 14.

By virtue of this arrangement of the diamonds and because of the provision of the auxiliary water grooves 22, there is a greater volume flow of drilling fluid across the working face of the core bit, yet the auxiliary grooves serve to carry off the excess of drilling fluid on the outside diameter, where the diamonds are flush and therefore more strongly set. The diamonds 19a that are set flush, or substantially so, do not do any actual cutting, nor do they regrind cuttings produced by the diamonds on the convex face of the core bit, but the diamonds 19a do serve to maintain the gauge of the hole. The over-all result is that the diamond set core bit of my present invention can be more adequately served by the same volume of cooling fluid and consequently kept cooler, than in the case of similar core bits heretofore used but not employing the auxiliary water grooves nor the particular setting arrangement for the diamonds.

It might be pointed out that if all of the diamonds over the entire drilling and reaming faces of the bit were set so as to protrude a substantial distance, as indicated at 19, there probably would be no need for the auxiliary water grooves, since the diamond points would space the metal surface sufficiently from the surface being drilled to provide for the necessary volume flow of drilling fluid over the working face of the drill. However, where relatively small diamonds are used, say from two to ten diamonds to the carat, it is not practical to expose the diamonds to the same extent, but they must be set differently for maximum effective life. As illustrated, such smaller diamonds should be set so that those diamonds along the highest annular area of the convex face 14 project the farthest and the extent of projection of the other diamonds progressively decreases toward the outside and inside surfaces 13 and 12, respectively, where the diamonds are set flush with the surface of the matrix, as at 19a. It has to be a gradual progressive lessening of the extent of projection of the diamonds from the surface, since otherwise the diamonds protruding the most, if set next to diamonds set flush, or nearly so, would readily break off. Thus, the auxiliary water grooves 22 are necessary for relief of the drilling fluid where the diamonds are set flush or nearly so, toward and along the outer surface 13. The provision of such auxiliary water grooves, therefore, makes possible the most effective use of relatively small diamonds because such diamonds can then be set to best advantage in the manner shown and described herein.

It is evident that many modifications may be made to the present invention without departing from the principle of the invention disclosed, and it is not my intention to limit the invention to any single embodiment, but limited only as necessitated by the scope of the appended claim.

I claim as my invention:

A core bit comprising an annular body having a working face formed of a convex end surface and inner and outer surfaces extending therefrom that are concentric and substantially cylindrical, said inner and outer surfaces having re-

lieved ends lying in axially spaced planes, abrasive particles set in said working face and extending in rows diverging outwardly over said convex end surface and in generally parallel rows extending axially along said inner and outer surfaces, the abrasive particles in said outer surface lying substantially flush therewith but those in said end surface protruding substantially therefrom, said surfaces being provided with main water courses lying in planes through the axis of said body and extending transversely of said body across all of said surfaces to the relieved inner and outer ends and dividing said end surface into sector-shaped portions, said end and outer surfaces being provided with auxiliary water grooves intermediate said water courses and beginning near the middle of said sector-shaped portions and extending therefrom along

said end surface and said outer surfaces to the relieved end of said outer surface.
